ION TRAP

Myron R. Heppner, Round Lake, Ill.

Application June 21, 1950, Serial No. 169,418

3 Claims. (CL 313—75)

1

This invention relates to improvements in an ion trap for cathode ray tubes and refers particularly to an improved economically constructed, conveniently attached ion tray construction.

In the operation of the usual cathode ray tube the discharge of electrons in the form of a stream within the tube is accompanied by ionization of residual and occluded gases within the tube. Bombardment by the ions so formed upon the fluorescent screen of the tube very quickly destroys the fluorescent screen.

It is known that electrons are responsive to a magnetic field and a stream of electrons may be diverted when acted upon by a magnetic field. The same holds true for ions except that the degree of diversion of a stream of electrons and a stream of ions when acted upon by a predetermined magnetic field is different, the electron stream being diverted to a greater extent than the ion stream.

Advantage is taken of this phenomena in the use of a cathode ray tube by disposing in the neck of the tube a barrier having a relatively small substantially centrally positioned opening; discharging the electron stream at an angle to the axis of the opening in the barrier and passing the stream of electrons and accompanying ions through a magnetic field between the discharge gun and the barrier, to bend both streams. The field is so controlled as to bend or orient the electron stream so that it moves through the opening in a more or less axial fashion with respect to the tube. The accompanying ion stream, however, being acted upon by the same field, but not being diverted to the extent of the diversion of the electron stream, strikes the barrier, that is, the electron stream is caused to miss the opening. In effect, therefore, the ions are "filtered" from the electrons and cannot exert their destructive effect upon the fluorescent screen.

The present invention relates particularly to a magnetic field-producing device, commonly referred to as an ion trap, which may be conveniently mounted upon the neck of a cathode ray tube to divert or bend the electron stream and the ion stream to axially orient the former and cause the latter to be obstructed.

As a feature of the present invention an ion trap is contemplated which is simple in construction, its workable elements or poles, whose primary function is to selectively orient the electron stream, functioning additionally to mount the device on the tube neck.

A further feature of the invention resides in a construction which is light in weight; is eco-

2

nomic in construction and which is efficient in operation.

Other objects, features and advantages of the present invention will be apparent from the accompanying drawing and following detailed description.

In the drawing,

Fig. 1 is a side view of a conventional cathode ray tube, parts being broken away and parts being shown in section, illustrating my ion trap mounted upon the neck of the tube.

Fig. 2 is a fragmentary detailed top plan view of a portion of the neck of the tube.

Fig. 3 is a transverse sectional view taken on line 3—3 of Fig. 1.

Fig. 4 is an enlarged sectional view taken through one of my improved units.

Fig. 5 is a detailed perspective view of the magnet retainer clamp.

Fig. 6 is a fragmentary perspective view of a portion of the magnet retainer.

Referring in detail to the drawing, 1 indicates generally a conventional cathode ray tube having a restricted neck 2 and a flared forward portion

3. A face 4 is carried at the flared end of the tube, the inner surface of the face carrying a fluorescent screen 5. At the opposite end of the tube a base 6 is carried having contact prongs 7 for making contact with appropriate circuit elements for the tube.

Other elements are normally associated with the tube, such as the horizontal and vertical controls, focusing and centering devices and the like. However, for purposes of clarity these elements are not shown, since, in themselves they are not interfunctionally related to the present invention.

The tube 1 carries interiorly thereof adjacent the base 6 a so-called electron gun 8 whose function is to discharge a stream of electrons designated by the dot-and-dash line. Intermediate the neck 2, a barrier 9 is carried having a substantially centrally positioned aperture 10. In this form of tube, the gun 8 is so arranged as to initially direct the electron stream at an angle to the axis of the tube, as indicated at 11 in Fig. 1. Eventually, the stream of electrons is projected through aperture 10 substantially along the axis of the tube, as indicated at 12 in Fig. 1, after the stream has been bent and oriented as will be hereinafter more fully described.

The device contemplated in the present invention comprises a unit assembly 13 including arms 14 and 15, a magnet retaining portion 16, a magnet retaining clamp 17 and a magnet 18. The

arms 14 and 15 and the magnet retaining portion 16 are formed from a strip of ferro-magnetic material such as steel and are possessed of sufficient resiliency to engage the neck 2 of the tube 1, as shown best in Fig. 3, the arms being arcuately curved and the ends 19 of the arms being spaced from each other and being outwardly turned. Intermediate arms 14 and 15, the strip is bent to form a substantially channel section, as shown best in Fig. 6 to embrace the rectangular sectioned permanent magnet 18.

To secure the magnet 18 firmly in contact with the walls of the magnet retaining portion 16 so that a path of minimum reluctance is offered to the flux between the surfaces of the magnet and the surfaces of the portion 16, the clamp 17 is employed.

The clamp 17 is substantially channel shaped, having side flanges 20 and a central web portion 21. At the ends of the flanges 20 inturned tongues 22 are formed. The clamp 17 is constructed of a non-magnetic metal such as brass, bronze or the like and is of sufficient thickness to rigidly clamp the magnet 18 and retaining portion 16 in intimate contact with each other.

In assembling the device 13 a straight strip of ferro-magnetic material, such as steel, is bent intermediate its length to form the channel-shaped magnet-retaining portion 16. The arms 14 and 15, at this stage are not curved, but comprise straight continuations of the flanges of the channel-shaped portion 16, the arms being disposed parallel to each other. The member 17 is then threaded upon the ends of the arms, the arms being respectively positioned in slots 23 at each end of the device 17 between the tongues 22 and web 21. Magnet 18 is positioned in the portion 16 and the clamp 17 is moved along the then straight arms 14 and 15 until the web 21 abuts the lower face (Fig. 4) of the magnet. The arms 14 and 15 are then arcuately shaped, as shown, and the webs 20 of the clamp 17 are squeezed inwardly into snug contact with the side edges of the magnet and tongues 22 are moved downwardly (Fig. 4) into contact with the respective arms 14 and 15. The clamping member 17 thus securely wraps the magnet-retaining portion 16 into snug contact with the magnet and holds these elements in relatively efficient magnetic contact with each other.

As has been hereinbefore described, arms 14 and 15 embrace the neck 2 of the tube 1 and are possessed of the requisite resiliency to hold the device 13 relatively immovable upon the tube. In order to facilitate the gripping action of the arms, elastic sleeves 24 and 25 may embrace the arms 14 and 15, respectively, adjacent the portion 16. For convenience, the sleeve 24 may be of a different color than the sleeve 25. For example, sleeve 24 may be red and sleeve 25 may be black, as indicated in Fig. 3. Arms 14 and 15, being of magnetic material and respectively contacting opposite ends of the magnet 18, are of different polarity. By the provision of the colored sleeves 24 and 25, the polarity of the arms may be conveniently coded and identified.

The ferro-magnetic strip comprising the arms 14 and 15 and the channel portion 16, prior to being bent and assembled as hereinbefore described, is provided with an aperture 26 which is preferably positioned at the central portion of the strip. It will be noted that the provision of the aperture 26 forms relatively restricted connecting portions 27 (Fig. 2) which form a magnetic path between opposite ends of the magnet 18. The

restricted dimensions of the connecting members 27 are such that they are saturated by the magnet 18 and hence a difference of magnetic potential is established between the arms 14 and 15. As will be hereinafter more fully described, it is this difference in magnetic potential which establishes the magnetic field through which the electron and ion streams are passed and which orients the electron stream axially so that it passes through the central aperture 10 in the barrier 8 while simultaneously causing the ion stream to impinge upon the barrier.

In employing my invention the unit 13 is positioned upon the neck 2 of the cathode ray tube 1 and is so disposed lengthwise along the neck 2 that the electron stream 11 will be so diverted or bent as to pass through the aperture 10. Of course, the strength of the magnet 18 taken in conjunction with the size of the aperture 26, which in turn, effectively determines the dimensions of the connecting paths 27, are correlated so that the electron stream is bent from its path 11 to the path 12 (Fig. 1).

Although, in illustrating the use of my invention, one unit 13 is employed to properly segregate the ion and electron streams, it is to be understood that two or more such units may be employed if desired depending upon the direction of discharge of the electron stream from the electron gun and the angle which the initially discharged stream makes with the axial center of the tube.

I claim as my invention:

1. A permanent magnet structure for use as an ion trap for a cathode ray tube comprising a one-piece ferro-magnetic strip, a permanent magnet having a north and south pole embraced by and in magnetic contact with an intermediate portion of said strip, non-magnetic means for 35 clamping said intermediate portion in snug contact with the north and south poles of said magnet, said strip terminating in oppositely extending spaced arms for embracing the neck of a cathode ray tube, an intermediate portion of said strip 40 adjacent its contact with said magnet and between said north and south poles of being of relatively restricted sectional dimensions and being magnetically saturated by the magnet embraced.

2. A permanent magnet structure for use as an ion trap for a cathode ray tube comprising a relatively elongated, relatively thin one-piece strip of resilient ferro-magnetic material, a channel formed intermediate the length of said strip, a permanent magnet positioned in said channel, a non-magnetic clamp for holding said strip in snug magnetic contact with said magnet at its ends and a side thereof, said channel being provided with an aperture to form of said channel magnetic paths of restricted cross section between the ends of said magnet, restricted cross-sectional portions of said channel being saturated by said magnet, said strip terminating in spaced arcuate arms for resiliently embracing the neck 45 of a cathode ray tube to establish a magnetic field across said neck between said spaced arms.

3. A permanent magnet structure for use as an ion trap for a cathode ray tube comprising a relatively elongated, relatively thin one-piece strip 70 of resilient ferro-magnetic material, a rectangular channel formed intermediate the length of said strip, a permanent magnet of rectangular section positioned in said channel, a non-magnetic clamp for holding said strip in snug magnetic contact with said magnet at its ends and a

side thereof that portion of the channel in contact with the side of the magnet being provided with an aperture to form of said channel magnetic paths of restricted cross-section between the ends of said magnet, said restricted cross-sectional portions of said channel being magnetically saturated by said magnet, said strip terminating in spaced arcuate arms for resiliently embracing the neck of a cathode ray tube to establish a magnetic field across said neck between said spaced arms.
